[57] **ABSTRACT**

A flail blade having a surface conforming to a first curvature and upper and lower edges conforming to a second curvature. The flail blade is affixed to the end of a flail which is rotated within the housing of a lawn sweeping device. The flail blade travels adjacent the inside surface of the housing, the edges conforming to the curvature of the adjacent parts of the inside surface, the flail blade surface having an arcuate-shaped portion proximate its point of attachment to the end of the flail and having a planar-shaped portion contiguous with the arcuate-shaped portion at the end opposite the point of attachment to the flail and extending in a direction opposite the direction of travel of the flail.

FIG. 1

FIG. 2

FIG. 3

FIG. 4

FIG. 5

FIG. 6

FLAIL DEVICE AND LAWN CLEANING AND PACKING APPARATUS

BACKGROUND OF THE INVENTION

This invention relates to heavy-duty lawn vacuum cleaning and packing machines. More particularly the invention relates to such machines having a frustum-shaped housing with an air intake affixed thereto and tangentially disposed to the inside slanting wall of the frustum. Air is drawn through the intake, into the housing, and out the smaller opening of the housing by a blower. Debris which has been drawn into the housing is struck by rotating flails and driven out the larger opening of the housing into a receptacle affixed thereto.

Such a device is described in U.S. Pat. No. 3,755,992. The flail provided therein has a club head which rotates adjacent the inside wall of the housing. The shape of the club head is very like that of a golf club, having a flat surface and straight edges. When the receptacle is fully packed with debris, the club head tends to dig into the already packed debris, striking it back into the housing. And even when the receptacle is not fully packed, the club head tends to shred leaves and other debris before packing it into the receptacle. Both the shredding of the debris and the digging into packed debris result in friction and therefore slowed operation of the lawn cleaning and packing apparatus and much wastage of energy.

SUMMARY OF THE INVENTION

According to this invention a flail device is provided which is suitable for use in lawn cleaning and packing machines.

In lawn cleaning and packing machines which have a housing with a frustum-shaped portion, an intake duct affixed to the frustum portion, a blower for drawing air through the duct, into the housing, and out the small end of the housing, rotatable flails for striking debris out of the housing and into a receptacle affixed over the large end of the housing, and a baffle for preventing debris from falling back into the housing, a flail blade is provided at the outer end of the flail which travels adjacent the inside wall of the frustum when the flail is rotating.

The flail blade has a double curvature, the surface of the flail blade having a leading arcuate portion and a trailing planar portion contiguous therewith, which portions define a first curvature. The upper and lower edges of the flail blade define a second curvature which conforms to the surface of the inside wall of the frustum to which the lower edge is adjacent.

The flail blade is affixed to the flail at the arcuate portion, which is the leading portion as the flail is rotated. The trailing planar portion defines a plane parallel to the plane of the larger opening of the housing.

It is an object of this invention to provide a flail for a lawn cleaning and packing machine which renders the machine efficient to use.

It is another object of this invention to provide a flail for a lawn cleaning and packing machine which will not tend to shred debris before packing it into the receptacle of the machine.

Still another object of this invention is to provide a flail for a lawn cleaning and packing machine which will not dig into and therefore unpack debris which has

already been packed into the receptacle of the machine.

Another object of this invention is to provide a flail which would be both safer to operate and more durable.

These objects and other features and advantages of this invention will become readily apparent by reference to the following description when taken in conjunction with the accompanying drawings.

BRIEF DESCRIPTION OF THE DRAWINGS

The appended drawings illustrate the invention, wherein:

FIG. 1 is a side elevational view, partly in longitudinal section, depicting a lawn cleaning and packing machine utilizing the flails of this invention;

FIG. 2 is a perspective view of the housing of the lawn cleaning machine of FIG. 1, the receptacle for debris having been removed;

FIG. 3 is a perspective view of the housing as in FIG. 2, but with the baffle removed to show the flail structures;

FIG. 4 is an end elevational view of the housing with the flail structures removed;

FIG. 5 is an enlarged, fragmentary, perspective view of the flail structure of this invention; and

FIG. 6 is a sectional view of the housing taken along line 6-6 of FIG. 3 and showing the relationship of the flail structure to the inside surface of the housing.

DESCRIPTION OF THE PREFERRED EMBODIMENT

The lawn cleaning and packing machine, with which this invention is concerned, is depicted generally at 11 in FIG. 1. The machine 11 includes generally a platform 12, a blower unit 13, a receptacle 14, and a cleaning and packing unit 16.

The platform 12, shown in FIG. 1, includes a substantially rectangular base 17, having rear wheels 18 (only one is shown) and front casters 19 (only one is shown) affixed thereto. A handle 21 is affixed to the rear of the platform 12 for manual control of the machine 11. Rear and front blower unit mounting blocks 22, 23 are affixed to the rear of the platform 12. A housing mounting and sealing wall 24 is affixed toward the center of the platform 12. And a receptacle mounting block 26 is located at the front of the platform 12.

The blower unit 13, illustrated in FIG. 1, includes a motor 27 which operates a belt-and-pully structure 28 which in turn drives a rotary positive pump (not shown). A housing member 29 encloses the rotary pump and supports the motor 27. The housing member 29 is supported by the mounting blocks 22, 23. The shaft of the rotary blower extends out of the housing 29 at 30.

The receptacle 14, depicted in FIG. 1, includes an internal plastic bag 31 and an external cylindrical container 32 which is closed at one end. A handle 33 is affixed to the container 32. The bag 31 is affixed to the cleaning and package unit 16 at 34. The container 32 is mounted in the mounting and sealing wall 24 and upon the mounting block 26. An annular rubber sealing or check valve structure 35 is provided between the container 32 and wall 24. An exhaust conduit 36 is affixed between the housing member 29 and the receptacle 14. The conduit 36 passes through the wall 24 and

sealing structure 35, being located above the cleaning and packing unit 16.

The cleaning and packing unit 16, illustrated in FIG. 1, is affixed to the platform 12 between the blower unit 13 and receptacle 14. The unit 16 includes a housing, indicated generally at 37, having a frustum-shaped portion 38 and a cylindrical-shaped portion 39. The frustum portion 38 is affixed at its smaller end to the blower unit 13 and at its larger end is contiguous with the cylindrical portion 39 and is mounted in the wall 24. The bag 31 of the receptacle 14 is affixed to the cylindrical portion 39 at 34. The rotary blower shaft 30 extends through the frustum portion 38 along the central axis thereof.

Referring to FIGS. 1 and 2, an air intake 41 is tangentially affixed to the frustum portion 38. A flexible hose 42 is affixed to the intake 41, FIG. 4 discloses ribs 43 disposed arcuately upon the inside surface of the frustum portion 38. The ribs 43 are in a counter-clockwise manner as viewed in FIG. 4. A screen 44 is affixed over the smaller end of the frustum portion 38 leading into the housing 29 of the blower unit 13. Wiper blades 45 are affixed to the blower shaft extension 30 adjacent to the screen 44.

Referring to FIGS. 1 and 2, a circular baffle 46 having a rigid central portion 47 and a pliable edge 48 is freely coupled to the end of the blower shaft extension 30. The baffle 46 is centrally disposed in the large opening of the frustum portion 38.

The flail unit 49 is indicated most clearly in FIGS. 3 and 5. The flail unit 49 is affixed to the blower shaft extension 30 intermediate the wiper 45 and baffle 46 and includes a mounting block 51 which is affixed to the extension 30. The unit 49 also includes a plurality of uniformly radially spaced flails 52. Each flail 52 has a shaft 53 with a pin 54 affixed normal thereto near to an inner end portion 56 of the shaft 53. The portion 56 is formed normal to the shaft 53 and parallel to the pin 54 and is rotatably received by the mounting block 51 near one of its corners.

The improvement of this invention is directed to the outer ends of the flails 52 and is best illustrated in FIGS. 5 and 6. The shaft 53 of each flail 52 has a curved outer end portion 57 to which a flail blade or striking portion 58 is affixed. The flail blade 58 has a flat surface which includes a leading arcuate portion 59 and a trailing straight or planar portion 61 contiguous with the arcuate portion 59. The flail blade 58 also includes upper and lower curved edges 62, 63, a rounded trailing edge 64 and a sharply tapered leading edge 66. The flail blade 58 therefore conforms to two curvatures, a first curvature defined by the arcuate and planar portions 59, 61, and a second curvature defined by lower edge 63.

When the shafts 53 of the flails 52 are extended normal to the extension 30, the curved outer end portions 57 arc in a direction opposite that of the ribs 43 and also arc toward the large opening of the frustum portion 38 and away from the plane defined by the shafts 53. The straight portions 61 of the flail blades 58 define a plane which is adjacent to and parallel to the plane of the large opening of the frustum portion 38. The lower edge 63 conforms to the inner surface of the frustum 38. The part of the edge 63 contiguous with the straight portion 61 defines an arc of a circle, and the part of the edge 63 contiguous with the arcuate portion 59 defines a curve.

When in operation, the motor 27 drives the blower (not shown) which in turn draws air via the conduit 36 out of the receptacle 14 thereby aiding in early expansion of the bag 31. The check valve structure 35 is drawn against the container 32 thereby assuring a tight coupling. Air is also drawn into the housing 37 via the intake 41 and hose 42. The air enters the frustum portion 38 tangentially and thereby is forced to flow within the frustum 38 in a circular path. Particles of debris tend to flow outwardly toward the slanting wall of the frustum 38 and forward toward the large opening of the frustum 38. Should any particles attempt to enter the blower unit 13, they are stopped by the screen 44 and knocked outward by the wipers 45. The rotating flails 52 drive the debris particles past the pliable edge 48 of the baffle 46 and into the bag 31. The baffle 46 prevents the debris from returning to the frustum 38. The baffle 46 rotates with extension 30 but is freely coupled thereto so that should debris become packed 20 all the way up to the baffle 46, the baffle 46 can stop rotating without hampering the extension 30.

When the flails 52 are not being rotated, they hang directly downward or rest against the pliable edge 48 of the baffle 46. When rotating, the flails 52 are prevented from swinging too far past a perpendicular relationship with extension 30 by the pins 54 which will strike against the mounting block 51.

When the flails 52 are rotating, the arcuate portions 59 are leading and the straight portions 61 trailing. The flail blades 58 no longer utilize large amounts of energy while chopping up debris. The straight portions 61 do not extend past the large opening of the frustum 38, and therefore energy is no longer wasted by the flail blades 58 digging into already packed debris. The flail blades 58 are made safer since any hand or finger which may enter the large opening of the frustum 38 will be batted away rather than cut. Thus it can be seen that the objects of the invention have been satisfied.

Although a preferred embodiment has been disclosed herein, it is to be remembered that various modifications and alternate constructions can be made thereto without departing from the full scope of the invention, as defined in the appended claims.

I claim:

1. A vacuum cleaning and mechanical packing device comprising: a housing including a frustum-shaped portion with a first opening in the smaller end of said portion and a second opening in the larger end thereof, a fan connected to said housing outside said frustum-shaped portion communicating with said first opening to draw a stream of air therefrom, an intake duct for passage of air and debris having an outlet directed inwardly substantially tangentially and circumferentially to the tapered inner surface of said frustum-shaped portion near said first opening such that a stream of air and debris carried therein as a result of operation of said fan are drawn inwardly through said duct to form a circular stream within said frustum-shaped portion, the debris in said circular stream tending to move peripherally to be adjacent the conical surface of said frustum-shaped portion, a shaft rotatably mounted on the longitudinal axis of said housing, power means connected to said shaft to cause rotation thereof, a plurality of elongated flails, each having on one end thereof pivotal mounting means connected to said shaft at a point diametric to the conical surface within said frustum-shaped housing that is adjacent said second open-

ing, said pivotal means being distributed about said point of said shaft so that said flails extend on substantially equally spaced radii as they are extended outwardly from the shaft by centrifugal force during rotation of the shaft, the ends opposite said pivotal means turned at an angle to form respective paddle-like portions and the flails being of such length to permit said paddle-like portions to revolve adjacent said conical surface, said paddle-like ends also turned in a slanting direction toward said second opening along said conical surface such that said paddle-like ends slant rewardly relative to their direction of movement, a circular baffle disposed coaxially within said frustum-shaped portion between said second opening and said point of said shaft to which said flails are attached, the baffle having substantially shorter diameter than the diameter of the adjacent surface of said frustum-shaped portion to allow debris that is stuck by said flails to pass by the edge of said baffle, and a receptacle connected to said housing and communicating with said second opening 20

5

10

15

20

to receive debris forced around said baffle by operation of said flails, the improvement comprising:

each of said flails having a formation with a double curvature;

a first curvature seen by viewing a said flail in plan by looking down from a cross-section taken through the shaft for said flail, wherein said flail curves in a first portion away from said shaft toward the straight inner edge of the larger second opening of said frustum-shaped portion, and then wherein the flail terminates in a second trailing portion of a substantially planar nature disposed parallel the said straight inner edge; and

said second curvature seen by viewing a said flail in side elevation, said flail having upper and lower identically curved edges extended from said shaft, the lower edge of which is disposed contiguous and complimentary to the inner surface of said frustum-shaped portion.
